PRESSING MACHINE

Harry D. Forse, Anderson, Ind.

Application December 22, 1939, Serial No. 310,500

12 Claims. (Cl. 38—36)

This invention relates to a hand operated garment steaming press.

The chief object of this invention is to improve the operation of a press of the aforesaid character such a press being of the general character illustrated in the copending prior application, entitled, "Pressing machine," Serial No. 219,546, filed July 16, 1938, and insofar as the present invention is concerned, whatever is disclosed in said application and is common to the copending application, is specifically disclaimed herefrom.

One feature of the invention consists in providing means which are automatically operable in the movement of the head toward the buck when positioned in close proximity thereto for applying steam to the garment on the buck for the steaming of the garment.

Another chief feature of the invention consists in providing means for automatically locking the head in the buck engaging position, which engagement is maintained automatically for a predetermined interval for pressing purposes, and the like, and then the engagement is automatically disassociated.

A further chief feature of the invention consists in the provision of means for manually controlling the steam application to the head, if, as and when desired.

Still a further feature of the invention consists in means for manually controlling the locking arrangement so that the head may be disassociated from the buck whenever desired.

Another feature of the invention is in the provision of dual and dissimilar manual control means for moving the head into buck engagement and one of which includes a portion which is movable from a relatively exposed position into a relatively unexposed position for clearance purposes, as hereinafter pointed out.

Other objects and features of the invention will be set forth more fully hereinafter.

The full nature of the invention will be understood from the accompanying drawings and the following description and claims:

In the drawings,

Fig. 1 is a side elevational view of a garment press embodying the invention.

Fig. 2 is a top plan view thereof.

Fig. 3 is a side elevational view of the automatic and manual steaming control for the head structure.

Fig. 4 is a view showing the latter mechanism as well as the lock and release mechanism for locking the head.

Fig. 5 is a view showing the locking mechanism in releasing position.

In the drawings 10 indicates a conventional press structure provided with a pedestal 11 and extending upwardly therefrom and rearwardly is an arm arrangement 12. Extending also upwardly and forwardly of said arm structure is a neck arrangement 13 which suitably supports a relatively stationary buck 14. Associated with 10 the aforesaid, is an apron structure 15. All of the aforesaid is of conventional character.

Operatively associated with the buck structure is a head structure 16, the latter being suitably supported and carried by an arm arrangement 17 pivotally mounted at 18 near the upper end of the upwardly and rearwardly directed arm portion 12. The head is adjustably associated with said lever arrangement 17, as indicated at 19. A steam supply line 20 is adapted to supply steam to the head structure 16, the latter being of steam applying type. The steam supply to said head includes a valve arrangement, indicated generally by the numeral 21 in Fig. 2 and shown more particularly in Figs. 3 and 4.

25 Pivotaly supported at the upper end of the arm portion 12 is a lever arrangement 22, the same being pivotally mounted as at 23 and including a rearwardly directed portion 24. The forward end of said lever arrangement 22 is 30 bifurcated and is connected by means of a handle portion 25, see Fig. 2, also connects the bifurcated arm arrangements some distance rearwardly of the handle and rearwardly of said bar member 25a is an other connecting portion 25b, see Fig. 2.

35 Interposed between the base 10 and the end 24 of the lever arrangement 22 is a spring 26. A link arrangement 27 is connected at one end to the lever 22 and at the opposite end to a supplementary structure 28 as at 29. Interposed between the head supporting lever 17 and the auxiliary structure 28 is a spring 30 and the force and effect of the same is controlled by the rod 31 having the rearwardly and upwardly exposed hand wheel 32 at its upper end and the wing nut 33 for adjustment locking purposes.

40 The aforesaid description describes in a general way the type of press which is the subject matter of the previous and copending application. The wing nut 33 adjusts the tension of spring 30 between members 28 and 17. The hand-wheel 32 adjusts the relative position between members 28 and 22. When the end 24 of member 22 is elevated manually against its constraint, the head 16 is lowered into contact with

the buck. The handle 25 when grasped may assist in this movement and may be held down as long as desired. A lock holds the head down, if not manually held, until a predetermined interval has elapsed and then is released which in turn releases lever 22 to its constraint to automatically elevate the head from the buck to complete the pressing cycle.

Pivottally supported as at 34 is a lever structure 35 and the rearward end thereof is connected by a rod 36 to the free end 24, as it were, of the lever arrangement 22. The opposite end of the lever 35 is forked or bifurcated as indicated at 37, and connecting the bifurcations is a shaft 38. Slidably and pivotally mounted on said shaft is a lever extension 39 having the offset foot engageable portion 40.

Projecting into the kerf or slot between the portions 37 and from one of the portions, is a pin 41. The portion of extension 39 associated with the shaft 38 includes a plurality of openings 42, each of which is adapted to receive the pin 41. As shown in Figs. 1 and 2, the treadle portion 40 of the lever structure is positioned with reference to the main portion thereof, so that the treadle is exposed for foot engagement. Whenever foot operation is not desired, the treadle portion 39-40 may be elevated or slid upwardly on the shaft 38 so as to free the pin from the then associated recess 42, and when freed therefrom, the treadle portion of said lever may be swung from the full line position, as shown in Fig. 2 in the direction of the arrows, until the pin 41 registers with the desired opening 42. Upon release from the elevated position, the treadle portion of the lever will be locked in the non-interfering or clearing position. This leaves the press arranged so that it is only hand operated through the lever structure 22. If the treadle is positioned as shown in Figs. 1 and 2, the head may be either hand operated or foot operated.

Extending across the two arm portions of the bifurcated lever arrangement 22, is a shaft 50 and mounted thereon are two coil springs 51 and 151, each having their adjacent ends bearing on the collar portion 52 carried by a shaft. The remote ends are respectively associated with somewhat similar but complementary lever arrangements.

Herein, see Fig. 2, the upper or right hand lever arrangement is designated by the numeral 53 and the lower or left hand lever arrangement by the numeral 54. Each includes a rubber bumper member 55 which is adapted to engage the cross portion 25a, see Fig. 1. Each lever construction includes an inwardly directed finger engageable portion, for example, lever 53 includes the finger engageable portion 56, while lever 54 includes a finger engageable portion 57, and these, as shown in Fig. 2, are directed toward each other and are positioned in close proximity to the handle portion 25 of the lever arrangement 22.

Lever 53—see Fig. 3—is of bellcrank type and includes the arm portion 58 mounting a roller 59, see Figs. 2, 3 and 4. This roller 59 is adapted to engage an abutment 60 carried by a slidable rod 61. The rod 61 has an angular end portion 61a—see Fig. 2—connected to an arm 62 pivotally supported at 63—see Fig. 3—and it includes a notch 64 adapted to seat a pin 65 that constitutes part of the valve control. The valve, as previously set forth, is indicated by the numeral 21. The rod 61 has its opposite end guided, as indicated, see Fig. 3, as at 66 in the cross member

17a and constrained in the desired direction, if desired.

It will be apparent that depressing portion 56 of the lever 53 will cause the roller 59 to engage the abutment 60 which is adjustably supported as at 60a on the member or rod 61 and this causes the lever 62 to move clockwise, opening the valve 21 to supply steam to the head structure.

This arrangement also is adapted for automatic actuation in that when the lever 22 is moved down toward the buck, it carries with it the head supporting structure 17 and by reason of the position of the respective parts, the roller 59 will engage the abutment 60 and automatic application of steam to the head structure is obtained.

Oscillation of the manually operable hand lever means 22 toward and away from the buck when the head is in the vicinity of or in close proximity to the buck, therefore, insures intermittent application of steam to the head for garment steaming prior to garment pressing.

Reference now will be had more particularly to Figs. 1, 2, 4 and 5, relative to the other lever arrangement carried by the manually operable main lever arrangement 22. The lever 54 pivotally supported on the shaft 50, as previously described, includes a lateral extension 70—see Fig. 4. This extension is of sufficient length and is directed opposite to the direction of the finger engageable portion 57 so as to be juxtaposed relative to the rod 71. The latter is slidably supported in bracket 72, see Figs. 1 and 2, and includes angular end portion 73 which is receivable by an opening 74 in an arm 75—see Fig. 1—of a timing mechanism such as of door check character, the latter being indicated by the numeral 76. A stop pin 77 is provided to limit the counterclockwise movement of the arm 75—see Fig. 1.

The depending portion 54a of the lever 54 includes a recess 78 and a shoulder 79. The lever structure 17 mounts a bracket 80 and this bracket carries a pin and roller arrangement 81—see Fig. 4—more especially and said roller is adapted to bear on the shoulder 79. It will be observed that the end of the portion 54 as indicated at 54b adjacent the shoulder 78 is curved. The reason for that is that as the arm portion 22 is brought down carrying with it the lever portion 17, the face 54b engages the roller structure 81 and the lever 54 is tilted clockwise—see Fig. 1—until this latter lever clears the pin and then the pin seats in the recessed portion 78 and bears on the shoulder 79. This constitutes the lock for holding the two main lever arrangements together which automatically holds the head structure and locks the head structure in the buck engaging position.

It will be apparent that when the lateral finger engageable portion 57 is engaged by the operator through finger touch movement, or the like, this lever latch is released and the head structure as well as the manually operable lever structure 22 together with the lever structure 17 is released to the constraint imposed by the spring 26. Thus the operator has control of the press at all times.

Whenever automatic control is desired, it will be quite apparent that in the downward movement of the lever 22 toward the buck carrying with it lever structure 17 and the head, the lock latch arrangement is positioned in the locked position. Thereafter if the operator does not release the latch arrangement to permit the head to be moved away from the buck, the door check

mechanism indicated by the numeral 16 becomes effective because in its operation the arm 75 moves from the full line position shown in Fig. 1 to the dotted line position where it is stopped by the pin 77. In this movement, which is automatic due to air release or air bleed to the check mechanism, the rod 71 is moved toward the left—see Figs. 1 and 2—and in so doing the upwardly extending portion 90 of said rod 71, see Fig. 5, engages the lateral portion 70 of the lever 54 10 and tilts the lever clockwise just as if the operator had depressed the lock lever 54 by engaging the lateral portion 57. Therefore, the lock latch is automatically released and at the end of the predetermined time interval determinable by the adjustments to which the door check mechanism, generally indicated by the number 16, has been subjected. Thus, lock release may be automatically effected and in this respect this type of control is similar to the automatic or manual types of control for steam supply to the head structure. When release is effected, arm 22 moves upwardly and this carries member 54a upwardly but more especially to the right, see Fig. 5, which returns arm 75 to the full line position, see Fig. 1, from the dotted line (release) position. The only time 70 leaves 90 is when 54 is manually actuated for manual release.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. In a pressing machine having a buck, a head movable toward and away from the same, and hand lever means for manually moving the head in opposition to a constraint normally constraining the head to a position remote from the buck, the combination of an articulated treadle structure for moving the head in the same manner as the hand lever means, said treadle structure being pivoted for treadle operation of the head, said treadle having a foot engageable portion at one end, and hinge means interposed between the foot engageable portion and the treadle pivot permitting extended positioning of the foot engageable portion for foot actuation of the head or angular positioning of the portion for operator clearance purpose about the machine during hand operation thereof.

2. In a manually operable press including a buck, a head, means supporting said head adjacent the buck for movement toward and away from the buck and normally constrained toward the latter position and manually operable lever means for manually moving the head toward the buck in opposition to the constraint, the head being of garment steaming character, the combination of a steam supply to the head, valve means controlling said steam supply to the head, means automatically operable in and by the movement of the head and lever means and operable prior to head and buck engagement, for valve means operation for steam supply to the head immediately prior to head and buck engagement, and other means associated with the automatically operable means for maintaining the valve means

open for steam supply during at least the initial portion of such engagement.

3. In a manually operable press including a buck, a head, means supporting said head adjacent the buck for movement toward and away from the buck and normally constrained toward the latter position, and manually operable lever means for manually moving the head toward the buck in opposition to the constraint, the head being of garment steaming character, the combination of a steam supply to the head, valve means controlling said steam supply to the head, means automatically operable in and by the movement of the head and lever means and only immediately prior to head and buck engagement, for valve means operation for steam supply to the head immediately prior to head and buck engagement, and other means associated with the automatically operable means for maintaining the valve means open for steam supply during at least the initial portion of such engagement, slight oscillation of the head immediately prior to the buck engaging position of the head providing intermittent steaming of the garment on the buck.

4. In a manually operable press including a buck, a head, means supporting said head adjacent the buck for movement toward and away from the buck and normally constrained toward the latter position, and manually operable lever means for moving the head toward the buck in opposition to the constraint, the combination of manually releasable latch means for holding the head in buck engaging position, the manual engageable portion of the latch means being juxtapositioned relative to the manual engageable portion of the lever means, and time controlled means having operative association with said latch means for releasing same following expiration of a predetermined period, said time controlled means including mechanism operable in the movement of the head from the buck to restore said means to initial position ready for control, said mechanism being mechanically operable upon head engagement with the buck to initiate time control of the latch means.

5. In a manually operable press including a buck, a head, means supporting said head adjacent the buck for movement toward and away from the buck and normally constrained toward the latter position, and manually operable lever means for manually moving the head toward the buck in opposition to the constraint, the combination of manually releasable latch means for holding the head in buck engaging position, the manual engageable portion of the latch means being juxtapositioned relative to the manual engageable portion of the lever means, time controlled means for automatically releasing said latch means and automatically restored to initial position in the movement of the head from the buck, the head being of garment steaming character, valve means controlling steam supply to the head, means automatically operable in the movement of the head and lever means immediately prior to head and buck engagement for valve means operation for steam supply to the head immediately prior to head and buck engagement, and other means associated with the automatically operable means for maintaining the valve means open for steam supply during at least the initial portion of such engagement.

6. In a manually operable press including a buck, a head, means supporting said head ad-

jacent the buck for movement toward and away from the buck and normally constrained toward the latter position, and manually operable lever means for manually moving the head toward the buck in opposition to the constraint, the combination of latch means for holding the head in buck engaging position, time controlled means for automatically releasing said latch means and automatically restored to initial position in the movement of the head from the buck, the head being of garment steaming character, valve means controlling steam supply to the head, means automatically operable in the movement of the head and lever means immediately prior to head and buck engagement for valve means operation for steam supply to the head immediately prior to head and buck engagement, and other means associated with the automatically operable means for maintaining the valve means open for steam supply during at least the initial portion of such engagement.

7. In a manually operable press including a buck, a head, means supporting said head adjacent the buck for movement toward and away from the buck and normally constrained toward the latter position, and manually operable lever means for manually moving the head toward the buck in opposition to the constraint, the combination of manually releasable latch means for holding the head in buck engaging position, the manual engageable portion thereby being juxtaposed relative to the manual engageable portion of the lever means, time controlled means for automatically releasing said latch means and automatically restored to initial position in the movement of the head from the buck, the head being of garment steaming character, valve means controlling steam supply to the head, means automatically operable in the movement of the head and lever means immediately prior to head and buck engagement for valve means operation for steam supply to the head immediately prior to head and buck engagement, and other means associated with the automatically operable means for maintaining the valve means open for steam supply during at least the initial portion of such engagement, oscillation movement of the head immediately prior to buck engagement providing intermittent steaming of the garment on the buck.

8. In a manually operable press including a buck, a head, means supporting said head adjacent the buck for movement toward and away from the buck and normally constrained toward the latter position, and manually operable lever means for manually moving the head toward the buck in opposition to the constraint, the combination of latch means for holding the head in buck engaging position, time controlled means for automatically releasing said latch means and automatically restored to initial position in the movement of the head from the buck, the head being of garment steaming character, valve means controlling steam supply to the head, means automatically operable in the movement of the head and lever means immediately prior to head and buck engagement for valve means operation for steam supply to the head immediately prior to head and buck engagement, and other means associated with the automatically operable means for maintaining the valve means open for steam supply during at least the initial portion of such engagement, oscillation movement of the head immediately prior to buck engage-

ment providing intermittent steaming of the garment on the buck.

9. In a manually operable press including a buck, a head, means supporting said head adjacent the buck for movement toward and away from the buck and normally constrained toward the latter position, and manually operable lever means for manually moving the head toward the buck in opposition to the constraint, the combination of manually releasable latch means for holding the head in buck engaging position, the manual engageable portion thereby being juxtaposed relative to the manual engageable portion of the lever means, time controlled means for automatically releasing said latch means and automatically restored to initial position in the movement of the head from the buck, the head being of garment steaming character, valve means controlling steam supply to the head, means automatically operable in the movement of the head and lever means immediately prior to head and buck engagement for valve means operation for steam supply to the head immediately prior to head and buck engagement, and other means associated with the automatically operable means for maintaining the valve means open for steam supply during at least the initial portion of such engagement, and manually operable means juxtaposed relative to the manually engageable portion of the lever means for independent manual control of the steam supply to the head.

10. In a manually operable press including a buck, a head, means supporting said head adjacent the buck for movement toward and away from the buck and normally constrained toward the latter position, and manually operable lever means for manually moving the head toward the buck in opposition to the constraint, the combination of latch means for holding the head in buck engaging position, time controlled means for automatically releasing said latch means and automatically restored to initial position in the movement of the head from the buck, the head being of garment steaming character, valve means controlling steam supply to the head, means automatically operable in the movement of the head and lever means immediately prior to head and buck engagement for valve means operation for steam supply to the head immediately prior to head and buck engagement, and other means associated with the automatically operable means for maintaining the valve means open for steam supply during at least the initial portion of such engagement, oscillation movement of the head immediately prior to buck engagement providing intermittent steaming of the garment on the buck.

11. In a manually operable press including a buck, a head, means supporting said head adjacent the buck for movement toward and away from the buck and normally constrained toward the latter position, and manually operable lever means for manually moving the head toward the buck in opposition to the constraint, the combination of latch means for holding the head in buck engaging position time controlled means for automatically releasing said latch means and automatically restored to initial position in the movement of the head from the buck, the manually operable lever means being of dual character and including a hand operable lever and a foot operable treadle lever, and hand operable

latch release means, the hand engageable portions of the latch release and lever means being juxtapositioned relative to each other.

12. In a manually operable press including a buck, a head, means supporting said head adjacent the buck for movement toward and away from the buck and normally constrained toward the latter position, and manually operable lever means for moving the head toward the buck in opposition to the constraint, the combination of latch means for holding the head in buck engaging position, time controlled means for automatically releasing said latch means and automatically restored to initial position in the movement of the head from the buck, the manually operable lever means being of dual character and including a hand operable lever and a foot operable treadle lever, hand operable latch release means, the hand engageable portions of the latch release and lever means being juxtapositioned relative to each other, the head being of garment

steaming character, valve means controlling steam supply to the head, means automatically operable in the movement of the head and lever means immediately prior to head and buck engagement for valve means operation for steam supply to the head immediately prior to head and buck engagement, and other means associated with the automatically operable means for maintaining the valve means open for steam supply during at least the initial portion of such engagement, and manually operable means juxtapositioned relative to the manually engageable portion of the lever means for independent manual control of the steam supply to the head, the hand engageable portions of the manual latch release means and the manual valve control means being positioned side by side and immediately adjacent the hand engageable portion of the lever means.

HARRY D. FORSE.
